COMBINED HEAT EXCHANGE SYSTEM AND AUXILIARY
POWER PLANT FOR INTERNAL-COMBUSTION ENGINES
Filed Sept. 18, 1950

UNITED STATES PATENT OFFICE

2,581,747

COMBINED HEAT EXCHANGE SYSTEM AND
AUXILIARY POWER PLANT FOR INTERNAL-COMBUSTION ENGINES

Carl H. Block, Peoria Heights, Ill.

Application September 18, 1950, Serial No. 185,430

5 Claims. (Cl. 123—142.5)

1

In recent years, the Arctic regions of the world have come into considerable prominence from the point of view of military strategy. Pursuant to this point of view various military posts have been established in the Arctic regions and many maneuvers carried out for the testing of troops and their equipment against the unusual conditions prevailing there.

Among the more formidable obstacles encountered in Arctic regions is the effect of its extreme cold upon various mechanical machines and equipment. Ordinary devices adapted to function in temperate climates are found to operate very inefficiently or not at all under conditions of the extreme low temperatures. One of the most important failures in this respect is in connection with internal combustion engines used by a large variety of equipment including, tractors, airplanes, tanks, tank destroyers, bulldozers and other powered equipment.

Two particularly serious problems exist in connection with such engines. One is the difficulty of starting them in a cold condition and the other is in the low efficiency of the engine after it is warm, due to the heat losses represented by the differences in temperatures between the cooling system and the atmosphere and also between the exhaust gases and the atmosphere.

One of the general objects of the present invention is the provision of means for utilizing the waste heat of engines operating in Arctic climates or extremely cold temperatures to develop auxiliary power.

Another object is the provision of means for warming a cold motor in such cold climates so that it may be readily started.

A further object of the invention is the provision of a reversible heat exchange system which, when operated in one way, will cause the engine to become warm and, when operated in another way, will utilize the waste heat for conversion to useful work.

Other objects and advantages of the invention will be apparent from the following description considered together with the accompanying drawing which is a schematic diagram of the arrangement of elements of an embodiment of this invention in relation to an ordinary type of liquid cooled combustion engine.

Referring with more particularity to the drawing in which like numerals designate like parts, the numeral 11 designates the block of a liquid cooled engine and 12 its exhaust manifold. Within said manifold, a tubular coil 13 is disposed, the upper end of which is connected to a vertical boiler 14 through pipes 15 and 16. The boiler 14 is of the fire tube type. Hot gases from the furnace box 17 at the bottom may be supplied by any suitable means, such as torches.

The hot gases pass upward through the tubes

18 and out through the stack 19. A heat exchange fluid 20 is in the boiler around the tubes 18 and, therefore, receives heat from the tubes when hot gases pass through them. Suitable heat exchange fluids include methyl chloride, ammonia, sulfur dioxide, iso-butane and fluorinated compounds of the Freon family, such as Freon 12, Freon 21, Freon 22, Freon 11, Freon 111, Freon 112 and Freon 113.

The other end of the coil 13 is connected to a reversible heat exchange unit comprising a tank 21 containing a number of vertical tubes 22. The tubes are connected at the top and bottom to a head plate 23 and a crown plate 24, respectively, spaced from the top 25 and bottom 26 of the tank. The coil 13 is connected to the interior of the tank 21 by means of a pipe 27 entering just below the head plate 23. The top 25 of the tank is connected to the outlet of a centrifugal pump 28 by means of a pipe 29. The inlet of the pump 28 is connected to a point in the cooling system of the engine by a pipe 30. The bottom 26 of the tank is connected to another point in the cooling system through a pipe 31. By these means, liquid from the cooling jacket of the engine may be made to pass through the tubes 22 of the tank, pick up heat at this point and return to the engine jacket. Heat is furnished by the vapors of the gas from the boiler 14 when it is desired to heat the engine before starting it. Gases condensing in the tank 21 are returned to the boiler by means of a pipe 32, reversible pump 33 and pipe 34, hereinafter more fully explained.

The pump 33 is driven by a reversible electric motor 35 which receives electrical power from a generator 36. The generator is driven by a gas motor 37 which is powered from a vapor line 38 tapped into the main line 16 coming from the boiler. Another line 39 tapped into the main line furnishes gas for driving another vapor motor 40 connected to the pump 28. The exhaust lines 41 and 42, respectively, of said vapor motors, are connected to a pipe 43 leading to the intake line 44 of an air condenser 45.

Said air condenser comprises a pair of vertical manifold pipes 46 and 47 across which there is connected a plurality of horizontally disposed S-shaped tubes 48. The pipe 46 is the inlet manifold and it receives the vapor to be condensed. The vapor passes through the pipes 48, becomes condensed by the cold ambient atmosphere and collects in the outlet manifold 47 from which it is returned to the boiler 14 through pipe 49, pump 50 and pipes 51 and 34.

The pump 50 is driven by a third gas motor 52 receiving gas from a line 53 coming off one of the main lines 15 or 16 and exhausting into the line 44 through pipe 54.

To start the engine when it is cold or frozen, heat is supplied to the boiler 14 by means of blow

torches or other suitable means. This causes the heat exchange fluid in the boiler to vaporize. The vapors pass through pipes 15 and 16, manifold coil 13, pipe 21 and into the tank 21 where they are condensed. The condensate collects and becomes available for return to the boiler 14 when the pump 33 starts to function.

In the beginning, the pressure of the vapor from the boiler will be too small to operate the vapor motors 37, 40 and 52. However, as heat continues to be supplied to the boiler, the vapor pressure increases until it is sufficient to operate these motors. This causes the pump 28 to be operated thereby effecting a circulation of the liquid in the cooling jacket of the engine through the pipes 22. At the same time the electrical generator 36 is furnishing energy to the motor 35 for driving the pump 33 and thereby return the condensate to the boiler. As this operation continues, heat is supplied to the cooling system of the engine, thereby causing its necessary parts to become warm for starting.

When the engine parts have become sufficiently warm to permit starting the engine, it is started and the boiler is no longer heated. As a consequence of the starting of the engine, hot exhaust gases from the engine pass around the coil 13 and also a thermostat 55 which controls a reversing switch 56 on the electric motor 35. Reversing the motor 35 causes the pump 33 to reverse also, so that instead of this pump delivering liquid to the boiler 14 from the tank 21, it delivers it to the tank 21 from the line 51 coming from the condenser 45.

The normal operation of the engine causes the cooling system to become hot and part of this heat is dissipated to the heat exchange fluid as the liquid of the cooling system passes through the pipes 22. In other words, the function of the tank 21 is reversed; instead of acting as a means for heating the liquid of the cooling system, it acts as a preheater for heating the heat exchange fluid. Vapor generated at this point passes into the coil 13 which now takes on the function of a heater by absorbing heat from the exhaust gases of the engine, and creating a high gas pressure. This gas flows into the pipe 16 and from thence to the three vapor motors 37, 40 and 52 by means of the lines 38, 39 and 53, respectively. Additional vapor motors may be included at any point for auxiliary needs.

The electrical generator 36 may be of a size to generate an excess of power over that needed by the motor 35, which excess would be available for operating other auxiliary electrical units.

From the above description it may be seen that by the use of this invention a frozen or very cold engine may be warmed to a temperature necessary for starting and by the use of the same system, partially reversed, a portion of the waste heat generated by the normal operation of the engine can be converted to useful work.

It is to be understood that the heat exchange fluid used in the system should be one which is normally a liquid, and not a gas or solid, at the atmospheric temperature and pressure or the ranges of atmospheric temperatures and pressures to be encountered in any particular case.

Having thus described this invention, I claim:

1. In combination with an internal combustion engine having a liquid cooling jacket, a heat exchange unit comprising a tank, tubes in said tank, means for circulating liquid from said jacket through said tubes and back into the jacket,

means for passing a heat exchange fluid around said tubes, said last mentioned means including at least one condenser for changing said fluid from a gaseous state to a liquid state and at least one heater for changing said fluid from a liquid state to a gaseous state.

2. In combination with an internal combustion engine having a liquid cooling jacket and an exhaust manifold, a heat exchange unit comprising a tank, tubes in said tank, means for circulating liquid from said jacket through said tubes and back into the jacket, means for passing a heat exchange fluid around said tubes, said last mentioned means including a closed piping system containing at least one condenser for changing said fluid from a gaseous state to a liquid state and a coil in said manifold.

3. In combination with an internal combustion engine having a liquid cooling jacket, a heat exchange unit comprising a tank, tubes in said tank, means, including a pump, for circulating liquid from said jacket through said tubes and back into the jacket, means for passing a heat exchange fluid around said tubes, said last mentioned means including at least one condenser for changing said fluid from a gaseous state to a liquid state and at least one heater for changing said fluid from a liquid state to a gaseous state; a gas motor for driving said pump, and means for passing said fluid in a gaseous state through said gas motor.

4. In combination with an internal combustion engine having a liquid cooling jacket, a heat exchange unit comprising a tank, tubes in said tank, means for circulating liquid from said jacket through said tubes and back into the jacket, means for passing a heat exchange fluid around said tubes, said last mentioned means including a closed piping system containing at least one pump, one condenser for changing said fluid from a gaseous state to a liquid state and a heater for changing said fluid from a liquid state to a gaseous state, a gas motor for driving said pump, and means for passing said fluid in a gaseous state through said gas motor.

5. In combination with an internal combustion engine having a liquid cooling jacket and an exhaust manifold, a heat exchange unit comprising a tank, tubes in said tank, means for circulating liquid from said jacket through said tubes and back into the jacket, means for passing a heat exchange fluid around said tubes, said last mentioned means including a closed piping system containing a condenser for changing said fluid from a gaseous state to a liquid state, heaters for changing said fluid from a liquid state to a gaseous state, one of said heaters comprising a coil disposed in said exhaust manifold and means for reversing the flow of said fluid through said tank.
